[57] CLAIM

The ornamental design for a one piece end protector for an integrated circuit package, as shown and described.

DESCRIPTION

FIG. 1 is a left front perspective view of a one piece end protector for an integrated circuit package showing our new design;

FIG. 2 is a top plan view thereof on an enlarged scale; FIG. 3 is a front elevational view thereof on an enlarged scale, the rear elevational view being identical thereto; and

FIG. 4 is a bottom plan view thereof on an enlarged scale.
